LOCK FOR MAILBAG ROPE

Max W. Behnke, Chicago, Ill.

Application May 26, 1954, Serial No. 432,445

1 Claim. (Cl. 70—64)

The present invention relates to the locks for mail bag cords, and has for its main object the provision of a lock capable of receiving the ends of a cord looped around the neck of a bag, preventing an unauthorized person to have access to the bag short of breaking the cord.

Another object of the present invention is the provision of a cord lock of the character indicated capable of receiving therewithin the ends of a cord in a longitudinal relation, and so constructed as to be capable of sliding upon the ends of the cord toward the loop thereof, that is in the direction of the bag, and which may be wholly incapable of sliding upon the cord ends in the opposite direction, that is away from the bag.

A still further object of the present invention is the provision of the lock of the character indicated which may be capable of receiving a padlock, the shackle of which defines means for preventing the transverse shifting movement of the ends of the cord and of a lever co-acting therewith for maintaining the cord ends locked within the casing of the lock and preventing the shifting movement of the latter upon the cord ends.

A still further object of the present invention is to generally improve and render more efficient the locks for the purpose and of the character hereinabove indicated.

With the above general objects in view and others that will appear as the invention is better understood, the same consists in the novel construction, combination and arrangement of parts hereinafter more fully described, illustrated in the accompanying drawing and pointed out in the appended claim.

In the drawing forming a part of this application and in which like designating characters refer to corresponding parts throughout the several views;

Fig. 1 illustrates the operative position of the present lock and the co-acting padlock with a bag and a cord looped around the neck thereof;

Fig. 2 is an enlarged plan elevational view of the present lock in the operative position relative to two ends of a cord;

Fig. 3 is a side elevational view of the lock;

Fig. 4 is the bottom elevational view thereof;

Fig. 5 is a longitudinal cross sectional view through the lock with the cord ends in an operative position therewith;

Fig. 6 is an end elevational view of the present lock;

Fig. 7 is a transverse cross sectional view through the lock on line 7—7 of Fig. 3;

Fig. 8 is a cross sectional view on line 8—8 of Fig. 3;

Fig. 9 is a cross sectional view on line 9—9 of Fig. 3;

Fig. 10 is a cross sectional view on line 10—10 of Fig. 3;

Fig. 11 is a cross sectional view on line 11—11 of Fig. 3; and

Fig. 12 is an elevational view of the opposite end of the lock.

Referring in detail to the present drawing, in Fig. 1 there is shown a bag 13 for receiving mail or the like. Tightly looped around the neck of said bag 13 is rope or

2

cord 14, the two ends of which leading from the loop are intended to be engaged by the present lock generally indicated by 15 in Fig. 1.

Lock 15 includes an oblong base 16, provided at its center with a downwardly depending ridge 17. Along its side edges said base 16 is provided with downwardly converging flanges 18 for the purpose of receiving therewithin in a contactual relation the upwardly projecting and diverging flanges 19 of rectangular frame 20. Said flanges 18 exert strong frictional grip upon said flanges 19 for the purpose of preventing sliding or disengagement of said frame 20 from said base 16. The rear end of frame 20 is provided with an upwardly turned tongue 21 which contacts the underface of said base 16. Said frame 20 is in a spaced relation with said base 16.

The front end of said frame 20 is devoid of tongue 21 or of any other obstruction between said frame and said base 16 providing a slot through which a card or the like bearing the name, address or both, of the receiver, consignee or the like, may be inserted. The writing upon the card will be visible through the window defined by the four sides of said frame 20. As is apparent the card inserted through said slot at the front end of the lock will be maintained in position against displacement by virtue of the friction exerted thereon by the sides of said frame 20 at one side of the card, and by said ridge 17 at the opposite side thereof.

The lock further includes a case including a pair of parallelly disposed walls 22, which by their lower ends are riveted, soldered or otherwise rigidly attached to said base 16 in a longitudinal relation therewith and in a spaced relation with the side edges thereof, as is clearly seen in Figs. 6 to 12, inclusive.

Extending from the upper edges of the two side walls 22, adjacent each end thereof, is connecting strip 23. Connecting in a rigid relation each of said connecting strips 23 with said base 16, substantially centrally of the lock, is post 24, riveted or otherwise rigidly affixed by its ends to the respective connecting strip 23 and said base 16, as is clearly seen in Figs. 6, 10, 11 and 12. Each of said posts 24 divides the space defined by said side walls 22, strips 23 and base 16 into two equal spaces, within each of which one end of cord 14 may be accommodated, as is seen in Figs. 2 and 5.

Rearwardly of the front connecting strip 23 the upper edges of said side walls 22 are reduced for effecting recesses 25, for the purpose hereinafter specified. Rearwardly of said recesses 25 said side walls 22 are upwardly extended to define projections 26, each of which being provided with aperture 27, the two apertures 27 in the two projections 26 being in alinement, as is seen in Fig. 8.

Rearwardly of said projections 26 the two side walls 22 are connected at their upper edges by bridge plate 28. Rearwardly of said bridge plate 28 the two side walls 22 are provided with recesses 29, which are disposed forwardly of the rear connecting strip 23.

Co-acting with the case of the lock hereinabove described is lever 30, which may be of a flattened form, as seen in Fig. 8, and of the width substantially corresponding to the distance between two side plates 22. Said lever 30 is pivoted upon pin 31, in the proximity of the rear end of said lever 30, and on a plane slightly rearwardly of the plane upon which the said apertures 27 are located.

The front end of said lever 30 carries an integrally formed and upwardly projecting eye 32, which is of a width larger than the distance between said side plates 22 so that the side portions of said eye 32 project laterally beyond said side walls 22, as is clearly seen in Fig. 7. The recesses 25 in plates 22 permit shifting

movement of said eye 32 on a vertical plane to or away from said plates 22.

The rear end of said lever 30 is turned in an upward direction for defining tongue 33, the free end of which is roughened or knurled as at 34. Said tongue 33 is disposed below said bridge plate 28.

After cord 14 has been formed into one or more loops around the neck of bag 13 the ends of said cord 14 may then be knotted to tighten the loops around the bag neck, and thereupon the ends of the cord are passed under the front connecting strip 23, then through said eye 32, extended above lever 30 and then past said bridge plate 28 and above tongue 33, and thereupon under the rear connecting strip 23, as is seen in Figs. 2 and 5. Recesses 25 and 29 permit manual grasp of the ends of cord 14 in order to shift the same longitudinally of the lock until the ends of said cord pass through the rear end of the lock. Manual hold at the sides of eye 32 and upward pull exerted thereon will of course angularly shift the front end of lever 30 in an upward direction, causing thereby the angular downward shifting movement of tongue 33 away from bridge plate 28, thereby preventing any interference by said tongue 33 for the shifting of the cord ends. When the cord ends have been extended through the rear end of the lock, the extended ends of the cord may be manually grasped and manual hold of and upward shifting of eye 32 will facilitate shifting of the lock along the two ends of the cord until the front end of the lock comes in contact with the loops of the cord at the neck of bag 13, as is seen in Fig. 1.

Release of the manual hold at eye 32 will tend said eye 32 to shift in the opposite direction, that is toward the upper edges of side walls 22, by virtue of the gravity of the front end of lever 30 and of eye 32, thereby tending to bring the free end of tongue 33 in contact with the ends of cord 14 below said bridge plate 28. It is of course assumed that during this operation the position of the lock is identical with that shown in Fig. 5, that is with base 16 disposed in a downward direction, while connecting strips 23 and bridge plate 28 disposed in an upward direction. It is noted that the front end of lever 30 and eye 32 are heavier than the rear end of said lever, including said tongue 33, permitting the upward shifting movement of said tongue 33 in contact with the ends of cord 14. While in the position of the cord ends within the lock, as seen in Fig. 5, it is possible for the lock to be shifted along said cord ends towards the cord loop and the neck of bag 13, it is wholly impossible to shift said lock to the opposite direction, that is away from the bag, unless of course the front end of lever 30 is first shifted away from base 16 in order to release the engagement of tongue 33 with the cord ends. When this is done, the lock may then be freely shifted from the bag. It is of course noted that said tongue 33 and bridge plate 28 act as a clamping means for the cord ends, with the sharpened knurls at the free end of tongue 33 biting into the cord, for preventing the shifting of lock along the cord ends away from bag 13.

When the shackle of padlock 35 is inserted through the two apertures 27 in projections 26, the same will constitute a means for preventing the upward shifting movement of the front end of lever 30. The shackle bears against the cord ends immediately therebelow,

thereby eliminating any space for the angular movement of the front end of lever 30, no matter how much manual pull in the upward direction may be exerted upon eye 32.

Although it is conceivable that even with padlock 35 and its shackle in the operative position with the lock, as seen in Fig. 1, the lock may be shifted along the cord ends toward the cord loop around the neck of the bag, it is wholly impossible to shift the lock to the opposite direction, that is away from the bag, because on latter shifting tongue 33 would bite into the cord ends thereabove to either seriously damage, ravel or sever the cord ends. This result would of itself indicate the unauthorized tampering with the lock and the contents of the bag.

While there is described herein preferred embodiments of the present invention, it is nevertheless to be understood that minor changes may be made therein without departing from the spirit and scope of the invention as claimed.

What I claim as new is:

A lock for locking a pair of cord sections comprising a base, a pair of parallelly disposed walls in a substantially perpendicular relation with said base, said walls being rigidly affixed by their adjacent edges to said base, a bridge plate connecting the opposite edges of said walls, said bridge plate being in a spaced parallel relation with said base, a pair of projections extending from said walls ahead of said bridge plate and rising above the plane of the latter, said opposite edges of said walls being provided with recesses ahead of said projections, a single lever disposed between said walls in a pivoted relation therewith, said lever being of a width substantially equal to the distance between said walls, said lever being substantially in a parallel relation with said base, and an eye having a single wide aperture carried by the forward end of said lever, the opposite end of said lever being upturned for defining a tongue, said eye being wider than the distance between said walls for selectively permitting said eye to rest upon the edges of said walls within said recesses, said eye being adapted to receive the cord sections, said cord sections being passed over said lever and between said tongue and said bridge plate, when said eye rests upon the edges of said side walls within said recesses said tongue being adapted to press the cord sections against said bridge plate, said projections being provided with aligned apertures for receiving therewithin a padlock shackle to bear against the cord sections at points disposed therebelow and to maintain said eye in contact with the edges of said side walls adjacent said recesses and assist the clamping action of said tongue on said cord sections thereby preventing the shifting movement of the lock longitudinally of the cord sections in either direction.
